UNITED STATES PATENT OFFICE.

JOHN BOYLE, OF PEABODY, MASSACHUSETTS.

IGNITER FOR EXPLOSIVE-ENGINES.

No. 827,904.

Specification of Letters Patent.

Patented Aug. 7, 1906.

Application filed November 21, 1903. Serial No. 182,094.

To all whom it may concern:

Be it known that I, JOHN BOYLE, of Peabody, in the county of Essex and State of Massachusetts, have invented certain new and useful Improvements in Igniters for Explosion-Engines, of which the following is a specification.

This invention relates to explosion-engine igniters of the make-and-break variety, and its principal objects are the following: first, to maintain the contacts in clean condition; second, to separate the contacts by an abrupt or hammer break, and, third, to provide improved means for advancing and retarding the spark.

In the preferred embodiment which I have herein illustrated the movable electrode or sparking point is so mounted as to have a translative movement in addition to its movement of approach to and recession from the fixed electrode, so that while in contact with said fixed electrode the movable electrode rubs against the fixed electrode, and therefore keeps the surfaces bright and free from soot and corrosion. The movable electrode, as shown, is an oscillatory arm whose shaft is mounted in a sleeve which is tripped by the engine, the arrangement being such that the movement of said sleeve in addition to oscillating the arm shifts the same to impart the rubbing movement. The sleeve and electrode-arm are connected by a spring and provided with abutting shoulders, so that when the sleeve is released from its tripping device the spring causes it to give a hammer-blow to the stem of the electrode-arm, thus producing an abrupt separation of said arm from the fixed electrode. For advancing and retarding the spark the reciprocating rod which trips the aforesaid sleeve is mounted in a guiding-bearing which is shiftable laterally, so as to cause the path of the tripper on the end of said rod to include a greater or less arc of the tripped member on the sleeve, thereby timing the release of said sleeve with relation to the stroke of the engine.

Of the accompanying drawings, Figure 1 represents a side elevation of an explosion-engine provided with my improved igniter. Fig. 2 represents a section on line 2 2 of Fig. 1. Fig. 3 represents a partial section on line 3 3 of Fig. 2. Figs. 4 and 5 represent views of the electrodes in separated and contacting positions. Figs. 6 and 7 represent sections on the line 6 7 of Fig. 2, showing the corre-

sponding positions of the abutting shoulders on the sleeve and electrode-stem. Fig. 8 represents a vertical section of the tripping-rod. Fig. 9 represents a section on line 9 9 of Fig. 8. Fig. 10 represents an end elevation, showing a modified form of igniter. Fig. 11 represents a vertical section thereof. Figs. 12 and 13 represent horizontal sections thereof with the parts in different positions. Fig. 14 represents a section on line 14 14 of Fig. 11. Fig. 15 represents a detail section showing a modified form of tripper.

The same reference characters indicate the same parts in all the figures.

In the drawings, 20 is the engine-cylinder, and 21 the crank-shaft.

22 is the fixed electrode projecting inside of said cylinder through a plug 23, and 24 is a movable electrode in the form of an oscillating arm mounted on the inner end of a stem 25. In Figs. 1 to 7, inclusive, this stem is journaled eccentrically in an oscillatory sleeve 26, which itself is journaled in a removable bush 27, fixed in the cylinder-wall. On the part of said sleeve surrounding the outer end of the electrode-stem is a rigidly-mounted projecting arm or tripped member 29, provided with a bevel 30. On the outer end of the stem 25 is a fixed collar 31, having a shoulder 32, which co-operates with a complementary shoulder 33 on the sleeve 26, as best seen in Figs. 6 and 7. A helical spring 34 has its opposite ends connected, respectively, to the sleeve 26 and collar 31, and constitutes a yielding or compensating connection between the sleeve 26 and stem 25. A stop 35, formed on the bush 27, arrests the return movement of arm 29 after its release. The arm 29 is tripped by a dog 36, journaled on the upper end of a reciprocating engine-actuated rod 37, and having a spring connection 38 therewith.

The operation of the parts thus far described is as follows: On the upward movement of the rod 37 the dog 36 engages and oscillates the arm 29, thereby rocking the sleeve 26, and by its further movement releases it and permits its return to the stop 35. On the return movement of the rod 37 the dog 36 encounters the bevel 30 and is oscillated on its rod without affecting the arm 29. The initial oscillatory movement of the arm 29 is communicated by friction and through the spring 34 to the stem 25, bringing the electrode 24 into contact with the electrode 22. This contact arrests further oscillatory

movement of the electrode 24; but the arm 29 and sleeve 26 continue to rotate, the spring 34 yielding. This separates the shoulders 32 33. Owing to the eccentric journaling of stem 25 in sleeve 26, such continued rotation of the sleeve imparts a movement of translation to the stem and shifts it in the direction of the movable electrode 22, as illustrated in Fig. 5, thereby producing a rubbing contact between the electrodes 22 and 24. When the dog 36 has escaped upwardly past the arm 29, the tension of spring 34 returns said arm until the shoulders 32 33 come into contact, the spring at the same time reacting 15 against the stem 25, holding the movable electrode against the fixed one, while permitting the former to slide back, owing to the eccentricity of the sleeve 26 now rocking in the opposite direction, into the position occupied 20 by it when first brought into engagement with the fixed electrode. The inertia of the arm 29 and its sleeve 26 causes the abutment 33 to strike the other abutment with a sharp hammer-like blow and suddenly move- 25 the arm 29 back against the stop 35, thereby causing an abrupt separation of the electrodes 22 24 to cause an igniting-spark. Thus it will be seen that four motions are given the movable electrode. It is first moved into 30 contact with the fixed electrode, then laterally in rubbing engagement, then in a lateral return movement still in engagement with the fixed electrode, being held against it by the spring, and finally is removed from contact suddenly. The lateral rubbing action 35 in two directions is very important, as thereby the electrodes are effectively freed from soot, grease, &c., and kept bright and in the best possible condition. Also the separation 40 of the electrodes coming at the last part of the lateral movement of the movable one and being in a direction somewhat inclined to the fixed electrode, not directly away from it in a perpendicular line, causes a drawing action 45 which increases the length and duration of the spark, insuring a perfect ignition of the mixture. The tripping-rod 37 is pivoted at 39 to another rod 40, connected at its lower end with an eccentric 41 on the lay-shaft 21 50 and having its upper end guided in a bracket 42. Said bracket is formed with a lateral bearing for the trip-rod 37. Said block or guide for a block 44, which forms a guiding-bearing has oppositely-projecting threaded 55 stems 45, carrying nuts 46, which engage the ends of the guide 43. By manipulating these nuts the bearing 44 may be shifted laterally with respect to the longitudinal path of movement of rod 37, thereby causing an 60 earlier or later release of the arm 29 by the tripping-dog 36.

In Figs. 10 to 14, inclusive, is shown a modification wherein a sleeve 47, carrying the tripped arm 29, is mounted between a collar 65 50 on the electrode-stem 25 and the bush 27.

A projecting lug 48 on said sleeve is mounted between fixed cam members 49, giving the effect of a screw, whereby the stem 25 is shifted axially when the sleeve 47 is oscillated. A spring 34 connects the sleeve 47 and stem 70 25, as before, and the sleeve and stem are provided with abutting shoulders 32 33, having the same function as the abutting shoulders previously described. When the arm 29 is oscillated by the engine-actuated tripping 75 device, the electrode 24 is brought into contact with the electrode 22, and the members 48 49 produce an axial rubbing movement of the electrode 24. When the arm 29 is released, the spring 34 brings the shoulders 32 80 33 together, producing the hammer-break by the inertia of the parts and carrying the arm 29 back to the stop 35.

Fig. 15 shows a modified tripper comprising a pivoted dog 360, adapted to be swung in 85 the plane of the path of movement of tripper-rod 37 upon encountering the arm 29 on the return movement of said trip-rod, the dog being yieldingly actuated by a spring 380.

I claim—

1. In an explosion-engine igniter, coöperating rigid sparking electrodes, one of which is mounted for movements into contact with and recession from the other and for rubbing movements bodily in opposite directions 95 while in contact, and actuating means for imparting said movements to the movable electrode including an engine-operated member and an intermediate yielding device engaged therewith and with the movable electrode 100 for retaining the electrodes in contact while the rubbing movements take place.

2. In an explosion-engine igniter, an oscillatory electrode, a second electrode, an engine-actuated member imparting to said first 105 electrode oscillatory movements toward and away from the second electrode, and translatable movements thereto bodily in opposite directions in contact with the second electrode, and an external compensating connection between said oscillatory electrode and member for retaining said electrodes in contact during the translatable movements.

3. In an explosion-engine igniter, a relatively stationary electrode, a relatively movable electrode, relatively movable means for moving the same first toward and into contact with the relatively stationary electrode, then laterally bodily first in one and then in the opposite direction in contact with the stationary electrode, and finally away from the stationary electrode, and a resilient connection 120 between said movable electrode and said means.

4. In an explosion-engine igniter, an oscillatory sparking electrode having a stem, an oscillatory sleeve journaling said stem, engine-operated means for oscillating said sleeve, and a spring connected to said sleeve and stem.

5. In an explosion-engine igniter, an oscillatory sparking electrode having a stem, an oscillatory sleeve journaling said stem, an engine-actuated tripper for said sleeve, a spring connected to said sleeve and stem, and abutting shoulders on said sleeve and stem producing a hammer-break movement in said electrode upon release of said sleeve by the tripper.
- 10 6. In an explosion-engine igniter, an oscillatory electrode, an oscillatory tripped member connected therewith, a complementary electrode, means actuated by the oscillation of said tripped member for imparting a bodily shifting movement to said oscillatory electrode while in contact with said complementary electrode, and an engine-actuated tripper for advancing and suddenly releasing said tripped member.
- 15 7. In an explosion-engine, an oscillatory tripped member, engine-actuated means for moving and suddenly releasing said member, a fixed and an oscillatory electrode, a stem to which said oscillatory electrode is connected, a yielding engaging device for communicating oscillatory movement from said tripped member to said stem and for returning the tripped member after its release, and provisions whereby oscillation of said tripped member causes rubbing movements of said oscillatory electrode in opposite directions while in contact with said fixed electrode.
- 20 8. In an explosion-engine, a fixed and an oscillatory electrode, a stem to which said oscillatory electrode is connected, an oscillatory tripped member journaled upon said stem, engine-actuated means for moving in one direction and suddenly releasing said member, and a yielding member engaged with said stem and tripped member for communicating oscillatory motion from the tripped member to the oscillatory electrode, the parts being so constructed and arranged that oscillation of the tripped member moves the oscillatory electrode, giving it rubbing movements in opposite directions while in contact with the fixed electrode, and suddenly separates it from the latter, the yield-
- ing member holding said electrodes in contact while such rubbing movements take place.
- 25 9. In an explosion-engine igniter, an oscillatory sleeve, engine-actuated means for turning and suddenly releasing the same, and a movable electrode having a stem eccentrically journaled in said sleeve.
- 30 10. In an explosion-engine igniter, an oscillatory sleeve, engine-actuated means for turning and suddenly releasing the same, a movable electrode having a stem eccentrically journaled in said sleeve, and a spring connected to said sleeve and stem.
- 35 11. In an explosion-engine igniter, an oscillatory sleeve, engine-actuated means for turning and suddenly releasing the same, a movable electrode having a stem eccentrically journaled in said sleeve, abutting shoulders on said sleeve and stem, and a spring connecting said sleeve and stem.
- 40 12. In an explosion-engine igniter, a movable electrode, an oscillatory tripped member, a reciprocating engine-operated tripping-rod, a guiding bearing-block surrounding said rod, and provisions for shifting said bearing laterally with respect to the path of movement of the rod.
- 45 13. In an explosion-engine igniter, an oscillatory sparking electrode having a stem, an oscillatory sleeve journaling said stem, an engine-actuated tripper for said sleeve, a yielding device between said sleeve and stem for transmitting oscillatory movement from one to the other, a bearing-surface on the engine-cylinder acting on the sleeve to produce through rotation of the latter reciprocatory bodily movement of the stem, and abutting shoulders on said sleeve and stem producing a hammer-break movement in said electrode upon release of said sleeve by the tripper.

In testimony whereof I have affixed my signature in presence of two witnesses.

JOHN BOYLE.
